UNITED STATES PATENT OFFICE.

CARL F. DIECKMANN, OF CHICAGO, ILLINOIS, ASSIGNOR TO EUGENE DIETZGEN COMPANY, OF CHICAGO, ILLINOIS, A CORPORATION OF DELAWARE.

VERTICAL FILE.

1,385,524.

Specification of Letters Patent. Patented July 26, 1921.

Application filed April 26, 1920. Serial No. 376,543.

To all whom it may concern:

Be it known that I, CARL F. DIECKMANN, a citizen of the United States, residing at Chicago, in the county of Cook and State of Illinois, have invented a certain new and useful Improvement in Vertical Files, of which the following is a specification.

My invention relates to filing cabinets, and is concerned more particularly with so-called "vertical files" for the filing and vertical suspension of mechanical drawings, maps, charts, blue prints, filing envelopes and the like. To illustrate the general class of apparatus, reference is made to the Beckbissinger Patent No. 727,881. In these cabinets the sheets or envelopes are suspended from rods, and when it is desired to examine any particular file, it and the ones in front of it are transferred onto brackets mounted on the inside of the front near the top. The front is then swung forward, permitting the desired file to be examined. In the larger cabinets, for example, size 36"x42" or 36"x48" the weight of the loaded front is considerable, and the object of my invention is to provide means whereby the front, even when heavily loaded, may be readily brought either to an oblique position or to a horizontal position so that the file under examination will lie horizontal, as though it were on a desk or table. Contributory to this general object, it is my purpose to provide means for insuring smooth operation and for equalizing the movements of the two ends of the front to prevent binding or tilting as it moves from one position to another.

I accomplish my objects by the mechanism illustrated in the accompanying drawings in which—

Figure 1 is an end elevation of the assembled device showing the front in intermediate position. A portion of the cabinet is broken away to reveal the internal construction.

Fig. 2 is an elevation similar to Fig. 1 except that it is taken in section and the front is shown lowered to horizontal position.

Fig. 3 is a sectional elevation through the cabinet looking toward the left, Fig. 1.

Fig. 4 is a perspective view illustrating the manner in which the drawings or file envelopes are mounted upon rods and carried by the cabinet.

Fig. 5 is a sectional view on the line 5—5, Fig. 1.

Fig. 6 is a fragmentary view showing the inner end of the drop front, also the means for guiding and elevating the same.

Fig. 7 is a sectional view on the line 7—7, Fig. 2, and

Fig. 8 is a fragmentary view looking toward the right in Fig. 5.

Like numerals denote like parts throughout the several views.

In the particular form shown in the drawings, the cabinet has a back wall 1, two end walls 2—2, a bottom 3, and a hinged cover 4. The cabinet proper is open at the front and is provided with a movable front 6 by which the opening may be closed. When used as a "vertical filing cabinet," the drawings or envelopes typified by the element 8 in Figs. 3 and 4 are suspended from rods 9, the ends of which project onto stationary shelves or brackets 10 fastened on the inside of the end walls near the upper part thereof. Cooperating with the stationary brackets 10 are transfer brackets 12 fastened to the inside of the front 6. When the front is in closed position and the cover 4 raised the rods may be slipped or transferred over from the stationary to the movable brackets and when they have thus been transferred the front may be lowered, carrying the transferred files with it.

Two chains or cables 14, of fixed length, are attached at one end to the upper part of the cabinet as for example at the point 15, Fig. 2. At the other end these cables are fastened to the front about midway between the upper and lower edges thereof, but above the normal center of gravity when the front is lowered. There is a cable for each end of the front and the point of attachment to the front is indicated by the reference numerals 16.

Slotted bars 18 are fastened to the inside of the end walls at and parallel to the front edges thereof, and these form guides for pins 19 projecting from the brackets 20 secured to the ends of the front as shown in detail in Fig. 7. The parts are so proportioned that when the pins are at the lower end of the slots, they form trunnions or pivots about which the front may be swung from closed position to a half open position shown for example in Fig. 1. When the front reaches this half open position the cables 14 become taut and thus prevent further swinging movement centered at the lower ends of the

slots. As the center of gravity is lower than the point 16, the front has a tendency to maintain this half open position but when it is desired to bring the front to horizontal position, it may be accomplished in either one of two ways. If the load is not too heavy an ordinary person will be readily able to produce the necessary movement by pressing downward upon the upper edge of the front. 10 This will cause the front to swing about the points 16 as an axis, the pins 19 sliding upward in the slotted bars 18. But if the front is heavily loaded or the operator is possessed of relatively little strength, the necessary 15 movement can be produced by applying power to the lower edge of the front to elevate it.

The means which I have provided for thus elevating the lower edge of the front from 20 the half open to the full open position are illustrated more particularly in Figs. 1, 2, 3, 5, 6 and 8. The brackets 20 have arms 24, to the ends of which are attached lifting cables 25. I use the term "cable" in the 25 generic sense, for the same may consist of chains, light wire rope or suitable substitute. At the upper ends these cables pass over drums 26 rigidly fastened to jack shafts 28 journaled in the end walls 2 as shown in detail in Fig. 5. Integral with one of the 30 drums is a toothed gear wheel 29 which meshes with a pinion 30 fastened to a power shaft 32 driven by a hand wheel 33. Integral with each of the drums is a sprocket 34 over which trains a sprocket chain 36. 35 At the lower end these chains train over sprockets 38 rigidly fastened to an equalizer shaft 40 journaled near the bottom of the cabinet.

40 The operation will now be readily understood. When the cabinet is closed the files will hang vertically. When it is desired to refer to any given file the cover 4 is thrown back as shown in full lines in Figs. 1 and 2. 45 The operator then grasps the file required and transfers it and the ones in front of it to the brackets 12. He then lowers the front 6 as far as it will naturally go by gravity, that is, to a half open position as 50 shown in Fig. 1. The file may then be lifted out. If the operator prefers to employ the front as a desk upon which to examine the file, he either presses downward on the upper edge of the front and thus causes it to 55 swing to horizontal position, shown in Fig. 2, or grasps the hand wheel 33, or the handle 34 thereof and rotates it in a position to wind up the cables 25 upon the drums 26. This elevates the lower edge of the front, 60 causing the latter to swing to horizontal position, the points 16 acting somewhat after the manner of a pivot, as before. The parts are so balanced and proportioned that when the front has reached horizontal position it 65 will automatically remain there in spite of

the fact that the points 16 of attachment are nearer the upper than the lower edge of the front and the center of gravity is thus below the point. The reason is probably based upon three facts, first, that the slotted bars are oblique with their upper ends nearer the back of the cabinet than their lower ends (and also nearer the points 15 of attachment of the cables 14) and second, that when the front is horizontal and thus 75 the horizontal thrust of the front 6 toward the back of the cabinet is considerably increased. It will be evident by referring to Fig. 2 that the closer the upper end of the slots in the bars are brought to the points 80 15 of attachment, the more will be the force required to lower the inner edge of the front in the slots to return the front to the half open position. Thus in moving from 85 half open position shown in Fig. 1 to the full open or horizontal position shown in Fig. 2, the front passes through a critical position, on either side of which it will tend to maintain itself in the position to which it is adjusted. Another reason why the front tends to maintain itself in horizontal position is that when the cables 14 are more 90 nearly horizontal (as in the open position of the front) the friction of the pins against the side of the guide slots is considerably increased. On account of the positive connection between the two drums, through the chains 36 and their coöperating sprockets, and the equalizer shaft 40, the drums always 95 rotate the same amount in the same direction thus making it certain that the pins 19 will not bind in the slotted bars 18. Thus smooth and accurate operation is assured and on account of the reduction gearing, 100 very little effort is required of the operator. 105

When it is desired to close the cabinet the reverse operation takes place. As the portion of the front below the points of attachment 16 is heavier than the portion above, especially when the files are in place, 110 a mere paying out of the cables 25 is sufficient to cause the lower edge of the front to descend. When the pins 19 have reached the lower ends of the slotted bars 18 the front will be near enough to a vertical position to 115 enable the operator to close it with the exertion of very little effort.

Having thus described my invention, what I claim as new and desire to secure by Letters Patent is:

120 1. A filing cabinet having a movable front, supporting means pivotally attached to said front between its upper and lower ends, and a power device attached directly to the lower end of the front and adapted 125 to vary its elevation to thus control the angle of inclination of said front.

130 2. A filing cabinet having a movable front, means for pivotally supporting said front between its upper and lower ends, means

for guiding the lower end of said front, and a power device for controlling the elevation of the lower end of the front to thus control the angle of inclination of said front.

5 3. A filing cabinet having a movable front adapted at its lower end to articulately engage the cabinet to thereby permit the front to swing forward about its lower end as an axis, anchoring means adapted to hold the 10 front in half open position, and means for thereafter elevating the lower end of the front for moving it to full open position.

4. A vertical file comprising a cabinet, a movable front, a hinge at the lower edge of 15 the front for permitting the front to swing outward, means for anchoring the front to the cabinet at a point approximately midway between the upper and lower edge of the front, said hinge being slidable up and 20 down along the forward part of the cabinet, and a power device mounted on the cabinet for sliding the hinge to the desired elevation.

5. A vertical file comprising a cabinet 25 having an opening at the front, a movable front for closing said opening, means on said front for suspending the articles to be filed, anchoring means attached to said front above the center of gravity thereof, said 30 anchoring means being adapted to permit the front to be swung forward from the cabinet, and a power device for controlling the angle of inclination of the front about the point where the anchoring means is 35 anchored to the front.

6. A vertical file comprising a cabinet having an opening at the front, a movable front for closing said opening, means on 40 said front for suspending the articles to be filed, a cable fastened at one end to the upper portion of the cabinet and at the other end to the front above the center of gravity thereof, a hinge for securing the lower end of the front to the cabinet, a guide on the 45 cabinet for guiding said hinge in an approximately vertical direction along the cabinet, a second cable fastened to the lower end of the front, and a drum mounted in the cabinet for winding up the cable to thereby raise the lower end of the front and simultaneously lower the upper end of the 50 front.

7. A filing cabinet having an opening at the front, a front for closing said opening, 55 means at the two opposite ends of the front for suspending it, said suspending means being adapted to support the front approximately midway between the upper and lower edges thereof, a pair of lifting cables connected to said front near the bottom thereof

and at opposite ends thereof, means on the cabinet for pulling upward on said lifting cables, and means for equalizing the movement of said cables.

8. A vertical file comprising a cabinet 65 having an opening at the front, a movable front for closing said opening, a cable attached to said front above the center of gravity thereof and attached to the cabinet at a point above the point of attachment to 70 the front, a pair of lifting cables connected to said front near the bottom thereof and at opposite ends thereof, means for pulling upward on said lifting cable, and means for equalizing the movement of said two lifting 75 cables.

9. A vertical file having a cabinet open at the front, a front for closing said opening, a hinge at the lower edge of the front for connecting it to the cabinet, cables connected at one end to the upper portion of the cabinet and at the other end to the front for permitting the front to swing forward a limited amount, the hinge being slidable upward approximately toward the point of attachment of the cables to the cabinet, whereby when the hinge is in uppermost position the tension of the cables is more nearly in line with the plane of the front, thereby tending to maintain the hinge in uppermost 90 position.

10. In combination, a filing cabinet having a front provided with a hinge at its lower edge whereby it may swing outward from the cabinet, cables attached to the 95 front between the upper and lower edges thereof, the upper ends of the cables being anchored to the upper portion of the cabinet and adapted to limit the extent to which the front can swing outward, the hinge being slidable obliquely upward and inward approximately toward the point of attachment of the cables to the cabinet, and means for arresting the upward movement of the hinges when the front has approximately 100 reached horizontal position with the cables taut.

11. A filing cabinet having a movable front, means fastened to the cabinet near the top thereof and attached to the front approximately midway between the upper and lower ends thereof for pivotally supporting it, means for guiding the lower end of the front in an approximately vertical direction, and a power device attached directly 115 to the lower end of the front for varying the elevation thereof.

In witness whereof I have hereunto subscribed my name.

CARL F. DIECKMANN.
